[57] CLAIM

The ornamental design for a deck of playing cards with segmented numbers, as shown and described.

DESCRIPTION

FIG. 1 is a plan view of the front of the diamonds suit of a deck of playing cards with segmented numbers showing a first embodiment of my new design;

FIG. 2 is a plan view of the front of a representative card of the spades suit of my new design;

FIG. 3 is a plan view of the front of a representative card of the hearts suit of my new design;

FIG. 4 is a plan view of the front of a representative card of the clubs suit of my new design; and

FIG. 5 is a plan view of the front of a representative card of each suit of a second embodiment of my new design; the total number of cards being the same as that of the first embodiment.

The back of the playing cards is conventional.
